APPARATUS FOR AUTOMATIC WITHDRAWING OF PULP ARTICLES FROM MOLDS

Jean Wagner, Paris, France

Application November 17, 1948, Serial No. 60,426

Claims priority, application France
November 20, 1947

2 Claims. (Cl. 92—57)

1
The pieces or rough shapes obtained from pulp sucked up on to a mould then dried by suction present problems of withdrawal from moulds that are difficult to solve on account of their weakness owing to their moist condition.

A standard solution of this problem consists in using a counter-mould that is held over the dried rough shape by setting up a slight pressure in the mould or a lowering of pressure at the end of the counter-mould so that the rough shape mentioned works loose from the mould without getting out of shape and remains in the counter-mould; it is then comparatively easy to withdraw it from the counter-mould in order to send it to the drying appliances.

But the handlings involved in this way of application of the counter-mould, drawing of the rough shape out of the counter-mould and sending to the drying equipment, have various disadvantages, more particularly their high net cost and the serious dangers of change of shape that result in a high percentage of rejects.

The object of my invention is an appliance for automatic withdrawal from the mould, leading the pieces or rough shapes without any handling from the mould on which they are shaped up to an arrangement that guides them to the drying equipment.

It is characterised by the combination of the following component parts:

1. A watertight box carrying a counter-mould, this box being furnished with slides or similar guiding means.

2. Two arrangements of guides or slippers for these slides of which one is coaxial with the mould in the position that it assumes at the time of withdrawal from the mould and of which the other is vertical. These two arrangements converge at one of their ends on a turning plate furnished also with guides and able to take the box carrying the counter-mould coming from the first arrangement of slippers and to apply it to the second.

3. Means of drawing the box along the slippers, more particularly forks for drawing the box each connected to a chain actuated by a reciprocating motion parallel to one of the slippers, each fork being arranged so as to take a spindle fastened on the box and to draw it in the required direction.

4. The counter-mould, preferably, will be furnished with means of suction and, if necessary, of blowing respectively for the unsticking of the rough shapes and their lodgment on the travelling band.

2
The travelling band or similar contrivance, intended to take away the rough shapes to the drying equipment, will be located below the vertical guide.

5. The device works in the following manner: The box drawn by one of the forks along the first guides then caps the mould and the rough shape that it carries; by blowing through the mould or by suction through the counter-mould, the rough shape is loosened. Then both are again drawn up to the turning plate where the spindle of the form engages in the teeth of the second fork. The turning plate pivots and puts the slides opposite the second guides so that the box is located in a vertical position and headed downwards; it will prove of advantage, therefore, to provide a suction device so as to prevent the rough shapes from falling off at the wrong time. The second fork then draws the box up to the lower point of the second guides and the rough shapes are lodged on the travelling band that leads them to the drying equipment (should it so happen through stoppage of the suction effected through the counter-mould, and if necessary through a slight increase of pressure through the actual counter-mould).

30 With the rough shape lodged on the band, the second fork brings the empty box up to the turning plate where it is picked up again by the first fork, submitted to the first guides and goes back to the mould for withdrawing another rough shape.

35 Several counter-moulds may be combined in the same box and located in the same arrangement of guides while the moulding appliances are themselves located in a corresponding way below the tank containing the pulp.

40 The appliance may be designed either with male moulds and female counter-moulds and boxes, or a reverse arrangement may be adopted.

45 The times of stoppage of the various component parts of this arrangement: box, mould and removal device, will be employed to advantage for accompanying operations before drying such as stamping, affixing of color markings, opening of ports in the rough shapes, mechanical compression, etc.

50 The synchronizing of the various operations will be obtained in any suitable way.

55 The controls for the lowering of pressure (suctions) and for raising of pressure will be obtained either through a central system that may control likewise the movements of the various component parts of the appliance, or through these movements themselves.

3

For the clearer comprehension of my invention, an example showing the carrying out of it, is illustrated in the accompanying drawings, in which:

Fig. 1 illustrates in a diagrammatic way an elevational view of the appliance.

Fig. 2 is a diagrammatic plan view.

In these two figures the same component parts carry the same reference numbers.

The moulding appliance is made up of the wheel with four arms 1 located above the tank 2, each arm being furnished with a perforated type of mould, A, B, C or D, this wheel being provided in a standard manner with means (not shown) for suction or for an increase of pressure in the moulds. This wheel is moved by a pawl and ratchet device that causes it to advance by a quarter of a turn in an equal length of time.

The operations take place in the following order:

Mould A, suction of the pulp against the mould.

Mould B or C, drying by suction.

Mould D, withdrawal from the mould by stoppage of the suction and, in case of need, slight increase of pressure for the loosening of the rough shape 3. The direction of rotation is shown by the arrow 4.

The withdrawing gear is made up of the box 5 set on the spindle 6 that carries the slides 7; of the arrangements of slippers 8 and 9 and of the turning plate 10 (constituted by two wheels 10 furnished with slippers 11); of two drawing forks 12 and 13, the first 12 actuated by a reciprocating motion (shown by the arrows 14) parallel to the slippers 8, the second 13 actuated by a reciprocating motion (shown by the arrows 15) parallel to slippers 9. These forks will be set, for instance, on endless chains, such as 16 and 17 and going round return-pulleys such as 18, 19, 20 and 21.

The box will be furnished, preferably with a counter-mould 24 and with a device, not shown, enabling a slight lowering of pressure or a slight raising of pressure to be applied on the surface of the rough shape.

The appliance works in the following way:

The box drawn by the fork 12 moved by the chain 16 caps the mould D and the rough shape 3. There is then a stoppage of the suction induced in the mould D, next a slight excess of pressure in this mould or a slight suction in the counter-mould (or both) so as to loosen the rough shape from the mould and fit it to the bottom of the counter-mould without giving rise to any change in shape.

The fork 12 moved in the opposite direction by the chain 16 draws the box 5 and the counter-mould up to the turning plate 10 through the

4

gliding of the slides 7 in the guides or slippers 8, then 11. The spindle 6 of the box is then located between the teeth of the fork 13, in which the turning plate causes it to pivot clockwise until it is brought to a vertical position and the slides 7 are brought in the extension of the slippers 9. The fork 13 being mounted on the chain 17 the movement given the latter lowers the movable box as far as the lower point of the slippers 9, where the dumping of the rough shape takes place, for instance, by a slight raising of pressure in the box 5.

The rough shapes are thus deposited at 22, on the conveyor to the drying equipment that will be formed, for instance by a travelling band 23.

Meanwhile, the box goes back to take up its position in front of the moulding appliance and the cycle starts all over again. It must be understood clearly that the method and conditions of carrying out the appliance as illustrated in the drawing could not in any way impose any restriction on the scope of my invention.

What I claim is:

- 25 1. Apparatus for removing crude molded products formed on a mold by filtering pulp through the mold, comprising a mold carrier adapted for presenting molds successively, a movable box having an axis thereon, a counter-mold in said box; 30 a first horizontal fixed rectilinear guide on each side of the movable box in which the corresponding end of the movable box slides, a second vertical fixed guide of the same form as the first said guide, a rotatable plate between the said two guides having a rectilinear groove of a shape corresponding to that of the said guides, two entraining members positioned on both sides of said guides and each comprising a fork for covering the axis of the movable box.
- 35 2. Apparatus as claimed in claim 1 and including endless chains, forks on said endless chains, said forks being engageable with the axis of said movable box, said endless chains constituting means for moving said box.

40 JEAN WAGNER.
